ATTORNEY.

UNITED STATES PATENT OFFICE.

FRED A. HORN, OF DENVER, COLORADO.

DESIGN FOR A HIGHWAY ADVERTISING AND DIRECTING DEVICE.

55,947.

Specification for Design.

Patented Aug. 3, 1920.

Application filed October 1, 1919. Serial No. 327,792. Term of patent 7 years.

To all whom it may concern:

Be it known that I, FRED A. HORN, a citizen of the United States, residing at Denver, in the city and county of Denver and State of Colorado, have invented a new, original, and ornamental Design for a Highway Advertising and Directing Device, of which the following is a specification, reference being had to the accompanying drawing, forming part thereof.

The figure is a perspective view of a highway advertising and directing device.

The design is an automobile tire in natural color with a red arrow shooting through it.

I claim:

The ornamental design for a highway advertising and directing device, as shown and described.

FRED A. HORN.
